Reinhard Säxer

UNITED STATES PATENT OFFICE

THEODOR SAXER, OF RORSCHACH, SWITZERLAND

MASSAGE APPARATUS

Application filed May 5, 1928, Serial No. 275,490, and in Germany May 31, 1927.

My invention relates to massage apparatus and especially to apparatus of this kind which are made use of in electro-therapeutics.

The difficulty with such devices is the combination of the massage elements with the electric apparatus. In one kind of electro-therapeutical massage apparatus the electric current is produced in a stationary machine and wires connect this machine with the massage apparatus. This is very awkward especially with regard to the handling of the apparatus while applying it in bodily treatment. Others have mounted the electric machinery on top of the massage apparatus thereby making it very heavy and also providing it with portions sticking out and projecting therefrom, which are likely to hurt the person under treatment or the massaging person and which portions themselves are exposed to damaging influences.

According to my invention I am doing away with all these difficulties by providing a massage apparatus having one or several roller massage elements to which two handles are attached. In these handles which are hollow the electric battery and the inductive machinery are placed, preferably in such manner that they are easily accessible and can readily be exchanged, especially the batteries. These may for instance be ordinary flash light batteries for pocket use. The handles of the massage apparatus may have a metallic or other electrically conductive surface so that they form one of the electrodes.

Another main feature of my invention is the special construction of the second kind of electrode in combination with the massage elements. For the purpose of getting a good massaging effect and also ascertaining a perfect contact between the electrically conductive portions of the massaging element with the human body under treatment I provide for resilient and elastic massaging projections on the surface of the roller massage elements, and when these projections are compressed to a certain extent then the intermediate metal portions forming the second electrode come into contact with the body under treatment, so that now the electric current flows from the hands of the self massaging person

through its body to the portions thereof which at the time are being massaged. This has the advantage that the massaging surfaces of the roller elements have their resilient and elastic quality and are in no way altered to their disadvantage by insertion of electrically conductive metal parts, as wires or the like. Besides by my way of construction it is impossible that the outside metal electric parts of the apparatus become defective and also injuring of the human body by these parts is practically avoided.

Having given a general explanation of my invention I now want to point it out more in detail, referring to the drawings which represent an example embodying my invention.

Fig. 1 is a longitudinal section through the massage apparatus, the short middle portion of a roller being represented in view.

Fig. 2 is a cross section through the end of the left handle, taken on line A—A of Fig. 1.

Handle 1 and handle 2 are made of metal, such as brass, aluminium or the like. They are hollow, and handle 1 contains a dry battery 3. The middle electrode thereof is connected by an isolated wire 4 through the hollow shaft 5 to the inner coil of the electric inductor 6, which is situated within the hollow handle 2. The primary current then passes through the interrupting mechanism 7 to top cover 8 and from there through spring 9, handle 2, hollow shaft 5 and handle 1 to the outside electrode of battery 3 which is not isolated against handle 1.

The inductive current produced in the outer coil of the electric inductor 6 is drawn therefrom in different steps and these are connected to a kind of switch board, as may be seen from Fig. 2. There is a handle 10 adapted to be turned over about half its circumference, and connected to this handle is a metal connecting piece 11 which connects the different steps I, II, III and IV to point 0 which latter is in electric conductive connection with handle 2 and by means of shaft 5 also with handle 1. The second end of the outer coil is connected to the roller elements 13 which are made of metal. These again are in electric conductive connection with each other

by hollow shaft 14 around which they rotate when the device is in operation.

Rubber rings 15 are situated at distances over the circumference of the roller elements 18. When the device is in use the rubber will be compressed on the human body to such extent that the intermediate metal portions of the rollers will touch the body. Assuming that the device is used for self massaging the inductive electric current will now pass from the handles 1 and 2 through the hands, arms and other portions of the body to the spot which is under massaging treatment.

Thus my apparatus allows for easy and convenient application of inductive electric current in connection with self massage. Of course it will be possible to make changes in the construction of parts of the apparatus without deviating from the spirit of my invention, therefore I do not want to be limited to the details described or shown in the drawing.

What I claim is:

1. An electro-therapeutical massage apparatus comprising a roller massage element; a hollow handle thereto; and a source of inductive electric current contained in said handle; said roller massage element comprising elastic outward projections and intermediate metal portions situated inwardly of said projections; said elastic projections being adapted to be compressed down to the level of said intermediate metal portions; said handle being connected to one electrode 35 of said source of inductive electric current, said metal portions of said roller being connected to the other electrode of said source of inductive electric current.
2. An electro-therapeutical massage apparatus comprising a roller massage element; two hollow handles thereto; and means for producing an inductive electric current, said means being contained in said hollow handles; said roller massage element comprising elastic outward projections and metal portions situated inwardly of said projections; one of said handles being connected to one electrode of said electric current producing means, the other electrode thereof being connected to 50 said metal portions of said roller element.
3. An electric-therapeutical massage apparatus comprising a roller massage element; two hollow handles thereto; an electric battery contained in said handles; an electric inductor also contained in said handles; said roller massage element comprising elastic outward projections and intermediate metal portions situated inwardly of said projections; said elastic projections being adapted to be compressed down to the level of said intermediate metal portions; and means for electrically connecting said inductor to said handles and to said metal portions of said roller elements.
